LIQUID CONTAINER WITH NOZZLE, SUCH
FOR EXAMPLE AS OIL CANS OR THE LIKEJoseph Kaye Robinson, Finchley, London,
EnglandApplication March 4, 1932, Serial No. 596,861
In Great Britain March 4, 1931

5 Claims. (Cl. 221—33)

This invention refers to improvements in or relating to liquid holding vessels or containers provided with a spout or nozzle for pouring or delivering such liquid therefrom such for example as oil cans or the like.

Heretofore it has been well known in practice to provide the discharging end of the spout or nozzle of oil cans or the like with a cap or cover adapted to be screwed—or otherwise secured e. g.

10 slid—onto or into such discharge end of the nozzle to close the latter when the latter is not required for use, and adapted to be readily removed when it is desired to discharge the liquid from the nozzle; and also it has been well known in practice to provide such removable caps or covers with a pin or pricker secured thereto in such a way that when the cap or cover is placed in position on the discharge end of the nozzle said pin or pricker will enter the bore or barrel (passageway) of the nozzle end and thus clear the passageway or keep it clear at the discharge end of the nozzle; but it very frequently happens in use that when such detachable cap or cover (whether provided or not with a pin or pricker

25 as aforesaid) is removed from the nozzle and laid aside it becomes lost or mislaid or cannot be found when wanted to replace on the nozzle end; and the present invention is designed (inter alia) to overcome this drawback.

30 According to my present invention I provide on some external part of the spout or nozzle itself a mount or means for receiving and holding thereon the removable cap (whether provided with a pricker or not) which cap is completely detached from and separated from the spout or nozzle when removed from the end of the spout; said mount or means being affixed to or formed on the body of the spout itself and not affixed to or formed on any part of the body of the can.

40 This arrangement according to my present invention of forming or affixing to the spout itself the mount or means for receiving the cap when detached from the end of the spout has the advantage of helping the user, namely in guiding the detached cap (with or without pricker thereon) into or onto the mount or means on the spout for receiving said cap, inasmuch as the user (whether in the dark or otherwise) can use the outside of the spout as a guide to his fingers by sliding them along the spout itself to thus bring the detached cap up to and into or onto the mount or means for receiving said cap on said spout.

45 My present invention is as follows:—

50 I employ a removable cap or cover of the usual

type such as aforesaid or of any suitable character adapted to effect the closure of the discharge end of the spout or nozzle of an oil can or container or the like, the body of which can or container may be of any suitable shape and construction and such cap or cover may be provided or not with a pin or pricker adapted to enter the passageway at the discharge end of said spout or nozzle when the cap or cover is placed in position on the discharge end of said spout or nozzle; and according to this invention I provide on some external part of the nozzle or spout—advantageously near the base of the latter—a stub or projection or the like means for forming an auxiliary mount, or alternative mount, on to 10 or into which latter the said cap or cover can be screwed or slid or otherwise temporarily mounted or secured thereto when removed from the end of the nozzle to allow the discharge of liquid from the latter.

20 I will now describe my present invention with reference to the accompanying drawing, in which:—

25 Fig. 1 is a side view in elevation of an oil can of the portable or so called pocket type, the body part of which is circular and has the auxiliary mount according to my invention arranged and mounted near the base of the nozzle or spout.

30 Fig. 2 is a view looking in the direction of arrow 2 (Fig. 1) of the spout or nozzle removed (separate) from the body part of the can, and showing the cap or cover (provided with a pin or pricker) separate just above the discharge end of the nozzle or spout.

35 Fig. 3 is a plan view of Fig. 2.

40 Figs. 4 to 6 illustrate an alternative manner of attaching the mount to the detachable spout, viz:—

45 Fig. 4 is a side view in elevation of said spout or nozzle in which the mount (affixed to said spout) is not provided with wings or flanges to assist in attaching same as in Fig. 1.

50 Fig. 5 is a view in elevation looking in the direction of the arrow 4 (Fig. 4) of the spout or nozzle with the mount affixed thereto as in Fig. 4.

55 Fig. 6 is a plan view of Fig. 5.

Referring more particularly to Figs. 1 to 3:—
a is the body part of the can or container.

b is the removable spout or nozzle having 50 flange b¹ and screw b² at the base thereof for attaching same to the body a of the can.

c is the removable cap or cover adapted to be screwed on to the discharge end b³ of the spout; said cap or cover c being provided with the pin 55

or pricker c^1 , adapted to enter the bore or barrel at the discharge end b^3 of the spout or nozzle b .

d is the auxiliary mount attached to the nozzle b near the base of the latter; i. e., adjoining the flange b^1 .

Said auxiliary mount d may be fixed, formed, or mounted on the spout b in any suitable manner; e. g., by providing same with flanges d^2 , d^2 and brazing same and the mount d to said spout b .

Said auxiliary mount d is provided with an upwardly extending screw threaded projection d^1 on to which the cap or cover c can be screwed to temporarily secure same thereon when removed from the end of the nozzle or spout; said auxiliary mount d , and projection d^1 being provided with a hole d^3 (Fig. 3) to receive therein the pricker c^1 of the cap or cover c .

Referring now more particularly to Figs. 4 to 6:—

In this arrangement; the mount $d+$ has no flanges provided thereon (such as d^2 in Figs. 1 to 3) and is affixed to the spout b by brazing or soldering; or if desired this mount $d+$ may be formed integrally with the spout.

It will thus be seen that the screw cap or cover such as c , when removed from the discharge end of the spout or nozzle b , can be readily attached and secured on the auxiliary mount until required to be replaced on the end of the spout or nozzle.

The said auxiliary mount such as d or $d+$ may be arranged as shown parallel or thereabouts with the spout b , or if desired at any angle there-to or position thereon.

This invention may be employed in conjunction with oil cans or other vessels or containers for liquids having either a rigid spout or nozzle of either straight form or of any suitable curve or shape, or in conjunction with a flexible or partly flexible spout or nozzle of any suitable type.

I am aware that a prior proposal has been made to attach to the body of the can a holder for a pin cushion into which pin cushion the pin or pricker of a removable cap (such as aforesaid) can be stabbed when said cap is removed from the end of the spout; and also another prior proposal has been made to provide the body of an oil can with a receptacle sunk in said body of the can for receiving the cap and pricker (when removed from the end of the spout) in said receptacle; and furthermore I am aware that it has heretofore been proposed to construct a kettle of the kind wherein the spout of the kettle is provided with a screw plug and this screw plug attached to the kettle body or spout either by means of a chain or by attaching the

said screw plug to one end of a length of wire or rod the intermediate portion of which latter is slidably mounted within—and undetachably from—a guide or sleeve secured to the outside of the spout of the kettle; and I make no claim whatever to any such known or proposed construction.

What I claim is:—

1. An oil can including a removable delivery spout and a cap, means for detachably securing the cap over the open free end of the delivery spout, a projection on the spout including means for detachably securing the cap directly thereon when the latter is detached from the free end of the spout.

2. An oil can including a removable delivery spout having an exteriorly threaded open free end and an interiorly threaded cap adapted to be screwed onto the exteriorly threaded open end of the spout, and an externally threaded projection on the spout upon which the cap is adapted to be screwed when detached from the open free end of the spout.

3. An oil can including a removable delivery spout and a cap, means for detachably securing the cap over the open free end of the delivery spout, a spicular projection including means for detachably securing the cap thereon when the latter is detached from the free end of the spout, and a mount securing the spicular projection to the spout in the vicinity of the base of the latter and with its longitudinal axis substantially parallel to the longitudinal axis of the spout.

4. An oil can including a removable delivery spout and a cap, means for detachably securing the cap over the open free end of the delivery spout and including a pricker adapted to extend down into the bore of such spout, a bored projection on the spout including means for detachably securing the cap thereon when the latter is detached from the free end of the spout, the bore of the projection receiving the pricker.

5. An oil can including a removable delivery spout having an exteriorly threaded open free end and an interiorly threaded cap adapted to be screwed onto the exteriorly threaded end of the spout and including a pricker adapted to extend down into the bore of the spout, a bored externally threaded spicular projection upon which the cap is adapted to be screwed when detached from the free end of the spout, the bore of the projection receiving the pricker, and a mount securing the spicular projection to the spout in the vicinity of the base of the latter and with its longitudinal axis substantially parallel to the longitudinal axis of the spout.

JOSEPH KAYE ROBINSON.
